UNITED STATES PATENT OFFICE.

RASMUS HAGBARTH QUISLING, OF CHRISTIANSAND, NORWAY.

TIME-FUSE FOR PROJECTILES.

SPECIFICATION forming part of Letters Patent No. 679,896, dated July 30, 1901.

Application filed February 8, 1900. Serial No. 4,650. (No model.)

To all whom it may concern:

Be it known that I, RASMUS HAGBARTH QUISLING, a subject of the King of Sweden and Norway, residing at Christiansand, in the 5 Kingdom of Norway, have invented certain new and useful Improvements in Time-Fuses for Projectiles; and I do hereby declare the following to be a full, clear, and exact description of the invention, such as will enable others skilled in the art to which it appertains to make and use the same.

My invention relates to combination-fuses for projectiles, (shells;) and it has for one object the provision of means whereby the firing appliances are locked against action, so 15 that the projectile can be handled and transported with perfect safety.

The invention has for its further object the provision of means whereby the firing appliances can readily be released from the locking device and the time-fuse simultaneously timed.

Referring now to the accompanying drawings, Figure 1 is a vertical central section of 25 so much of a projectile as will be necessary to a full understanding of my invention. Fig. 2 is an elevation of Fig. 1. Figs. 3 and 4 are sections on line 3-3 of said Fig. 1, showing the locking-pawl in different positions. Fig. 5 is 30 a top plan view; Fig. 6, a longitudinal section; and Fig. 7 an under side view of a key organized to release the firing appliances and at the same time time the time-fuse, a part of the handle of the key being broken away.

As shown in Fig. 1, the fuse-body 11, which 35 constitutes the conical head of the projectile, has an axial chamber intersected at the point by a transverse chamber in communication with said axial chamber through a suitable 40 aperture in the axial line of said axial chamber. The transverse chamber is in communication with the lower part of the axial chamber through a passage 12', (shown in dotted lines,) and in said transverse chamber 45 is secured the primer 10. Into the axial chamber above its lower portion of greater diameter is screwed a supporting-disk for the percussion-hammer or firing-pin 17, whose lower end is of increased diameter and has 50 mounted thereon the concussion-anvil 18, whose conical head 19 co-operates with the concussion-hammer 15 to ignite the priming

20, carried by said hammer. The passage 12' is in communication with a passage 12", also shown in dotted lines in said Fig. 1, and said passage 12" is in communication through suitable passages with the priming carried by the revoluble fuse-ring, so that the fire from the primer 10 will be communicated through passage 12' to the igniting-charge in 60 the chamber 12^a below supporting-disk 12, while the fire from the priming on the fuse-rings will be communicated to the charge in said chamber 12^a through passages 12" and 12'. The upper conical portion of the fuse-body 11 constitutes the cap, said body being of reduced diameter below said cap portion and screw-threaded at its lower end, and on the smooth cylindrical portion are mounted the fuse-rings 40 and 41. The fuse-ring 40 70 is keyed to the fuse-body 11, so as to slide longitudinally thereon only, while the time-fuse ring 41 is free to revolve on said fuse-body when not locked or jammed.

The construction of the fuse-body, the fuse-rings, the percussion and concussion firing appliances, and the arrangement of the primings, so far as I have described them, are well known and, specifically speaking, form no part of this invention, which I will now describe. 75

Instead of screwing the fuse-body directly into the projectile I provide a sleeve 13, having a flange 13' a short distance from its upper end, which flange when the sleeve is screwed into the projectile bears upon a shoulder formed by a circular recess in the upper face of said projectile, while the upper or outer end of said sleeve when the fuse-body 11 is fully screwed into the same will bear on the non-revoluble but longitudinally-movable fuse-ring 40 and jam the revoluble fuse-ring 41 against the shoulder formed by the conical cap portion of the fuse-body 11 and lock it against rotation. 85

The sleeve 13 has a notch 27 in its upper 90 or outer portion above its flange 13', while the fuse-body 11 has a longitudinal slot 24, whose lower or inner end wall is in line with the upper or outer face of the supporting-disk 12, while its upper or outer end wall is in line 95 with the lower or inner edge of the head 19 of the concussion-anvil 18 and with the like edge of the concussion-hammer 15. The percussion-hammer 17 has a foot-flange 16 seated

in a circular recess in the supporting-disk 12, and, as clearly shown in Fig. 1, the arrangement of the percussion-hammer and the concussion-anvil is such as to form an annular chamber 25 between said supporting-disk 12 and the head 19 of said concussion-anvil. The revoluble fuse-ring 41 has a peripheral recess 42, and the non-revoluble fuse-ring 40 has a similar recess 29, and in the under side of said fuse-ring 40 is formed a suitable recess for locking-lever 21, fulcrumed on a pin 21' in said recess, said lever being acted upon by a spring 26.

The lever 21 has a nose 23 of a height equal to the length of the slot 24 in fuse-body 11 or equal to the distance between foot-flange 17 of percussion-hammer 16 and the head 19 of concussion-hammer 18, the aforesaid spring acting on the said lever to project its nose into chamber 25, and thus lock the firing appliances against motion, as shown in Fig. 1.

The lever 21 has a lug 26, (shown in dotted lines in Figs. 3 to 5,) adapted to engage the notch 27 in the sleeve 13, hereinbefore referred to, and said lug is of such a thickness as to prevent the fuse-body from being fully screwed into sleeve 13 when the lever 21 is in its locking position, so that said fuse-body cannot be screwed home, the firing appliances released, and fuse-ring 41 locked against rotation until the lever 21 has been moved against the stress of its spring to withdraw its nose 23 from chamber 25 in the fuse-body 11 and its lug 26 out of engagement with the notch 27 in outer end of sleeve 13. In order that the lever may be moved in the manner described, it has an angular heel 28, that projects into the peripheral recess 29 in fuse-ring 40, the outer end of said heel being flush with the outer face of said ring.

When the fuse-body is to be screwed into sleeve 13, the lever 21 is first moved out of its locking position and held there until the lug 26 engages the notch 27 in said sleeve, the lever being then free to return into its locking position under the stress of its spring; but owing to the thickness of said lug 26 the fuse-body cannot be fully screwed into its sleeve. To effect this and at the same time move the lever 21 into its unlocking position and to time the time-fuse, I employ an implement which I call a "key." (Shown in Figs. 6 to 8.) The key is composed of a fixed ring 51, having a chambered handle extension, in the chamber of which is revolubly mounted a worm 53 on a spindle 51', provided with a knob or milled head 51" for revolving the same, and on said spindle or formed integral with the worm is a toothed wheel 58, normally engaged by a tooth on the free end of a leaf-spring 56, secured in the handle-chamber and locking the worm against rotation. The tooth on said spring is moved out of engagement with the locking-wheel by means of a push-rod 55, guided by a pin 55', extending through a longitudinal slot in said rod, as clearly shown in Fig. 8. On ring 51 is

mounted to revolve a ring or worm-wheel 52, whose teeth 54 gear with the aforementioned worm 53, as shown in Fig. 6. The opening 70 in rings 51 and 52 is such as to accurately fit the conicity of the fuse-rings 40 and 41 when the key is applied to the fuse-body 11, and said ring 51 has a fixed lug 61, projecting from its inner periphery and so located that 75 when the key is applied to the fuse-body 11 it will engage the peripheral recess 42 in revoluble fuse-ring 41, while the ring 52 has a lug 60, which has radial motion, to which end it is secured to a spring 62, the position of 80 the resilient lug being such as to enter the peripheral recess 29 in fixed fuse-ring 40. The worm-wheel or ring 52 is graduated on its upper face, as shown in Fig. 5, and ring 51 has a segmental slot 51", in which a pointer 85 59 is adjustable, so that the angular relation of the lugs 60 and 61 can be varied in accordance with the adjustment of the pointer.

The operation of the key is as follows: After adjusting the angular relation of the lugs 90 60 and 61 by revolving the worm-wheel or ring 52 to the required extent and releasing the push-rod 55 to allow the tooth on spring 56 to engage the lock-wheel 58 the key is placed on the fuse-body and fixed lug 61 inserted into recess 42 in the revoluble fuse-ring 41. It has hereinbefore been stated that when the fuse-body 11 is screwed into the projectile-sleeve 13, with the lock-lever 21 in its locking position, Fig. 3, said body cannot 100 be fully screwed into its said sleeve, so as to cause its end to impinge upon the fixed fuse-ring 40 and cause the latter to jam the revoluble fuse-ring 41 and lock it against rotation. Now when the key is applied, as described, with the lug 61 in recess 42 of revoluble fuse-ring 41, as stated, and revolved in the proper direction from left to right, Figs. 1 and 3, on the fuse-body, said ring will be caused to revolve until the resilient lug 60 110 snaps into the recess 29 behind the heel 28 of lock-lever 21 on the left of Figs. 2 and 3. A further slight rotation of the key in the same direction will cause said lug 60 to turn the lock-lever until its nose 23 has been retracted from between the firing appliances, Fig. 4, at which time the lug 26 on said lever will also be clear of the notch 27 in the sleeve 13 above its flange 13', the parts then being 120 in their relative positions, Fig. 4, and further rotation of the key from left to right becomes impossible by reason of the abutment of the heel 28 of lever 21 against the right end wall of recess 29 in non-revoluble fuse-ring 40. During this rotation of the key the movable 125 fuse-ring 41 has also been revolved the required distance, or in accordance with the angular adjustment of lugs 60 and 61, and as the lug 26 on lever 21 is now clear of notch 27 in sleeve 13 said lever cannot return into 130 locking position and the fuse-body 11 can be fully screwed onto the said screw to jam and lock the fuse-ring 41 into its adjusted position, the projectile being now ready for the

gun. It will thus be seen that unless the key is applied to move the lever 21 out of engagement with the firing appliances and sleeve 13 it is impossible to fully secure the fuse-body 5 to or explode the projectile, while the action of the key not only disengages the lever from the parts described, but at the same time times the time-fuse.

Having thus described my invention, what 10 I claim as new therein, and desire to secure by Letters Patent, is—

1. The combination with the adjustable fuse-ring containing the time-circuit of a time-fuse for projectiles, firing appliances for igniting the priming of said fuse, and a locking device for locking said appliances out of operation; of means organized to operate the locking device to release the firing appliances and simultaneously therewith revolve 20 the fuse-ring and time the fuse, substantially as set forth.

2. The combination with the adjustable fuse-ring containing the time-circuit of a time-fuse for projectiles, firing appliances for firing the priming of said fuse and a locking device for locking said appliances out of operation; of means organized to operate the locking device to release the firing appliances and to simultaneously revolve the fuse- 25 ring and determine the amplitude of its rotation, for the purpose set forth.

3. The combination with the adjustable fuse-ring containing the time-circuit of a time-fuse for projectiles, firing appliances for igniting the priming of the fuse, and locking devices for locking said firing appliances out of operation and the fuse-ring against rotation; of means organized to operate the aforesaid locking devices to release the firing 35 appliances, to simultaneously revolve the fuse-ring and then to lock said ring against rotation, for the purpose set forth.

4. The combination with the adjustable fuse-ring containing the time-circuit of a time-fuse for projectiles, firing appliances for igniting the priming of the fuse, and locking devices for locking said firing appliances out of operation and the fuse-ring against rotation; of means organized to operate the aforesaid locking devices to release the firing 45 appliances, to simultaneously revolve the fuse-ring, determine the amplitude of its rotation 50 and then to lock said ring against rotation, for the purpose set forth.

and then to lock said ring against rotation, for the purpose set forth

5. The combination with the adjustable 55 fuse-ring containing the time-circuit of a time-fuse for projectiles, percussion and concussion firing appliances for firing the priming of the fuse and locking devices for locking said appliances out of operation and for locking the fuse-ring against rotation; of means organized to operate the aforesaid locking devices, release the firing appliances, revolve the fuse-ring and then lock it against rotation, for the purpose set forth.

6. The combination with the adjustable 60 fuse-ring containing the time-circuit of a time-fuse for projectiles, percussion and concussion firing appliances for firing the priming of the fuse and locking devices for locking 70 said appliances out of operation and for locking the fuse-ring against rotation; of means organized to operate the aforesaid locking devices, release the firing appliances, revolve the fuse-ring, determine the amplitude of its 75 rotation and then lock it against rotation, for the purpose set forth.

7. The combination with a projectile and a flanged internally-screw-threaded sleeve secured axially therein and having a notch in 80 its upper or outer end above the flange, the fuse-body 11 adapted to be screwed into said sleeve, the fuse-rings 40 and 41 mounted on said body, said ring 40 having longitudinal motion only and said ring 41 both longitudinal and rotary motion, percussion and concussion firing appliances contained in said fuse-body and a locking-lever adapted to lock said appliances out of operation and to lock the fuse-body against being fully screwed 85 into its sleeve; of means organized to release the firing appliances and at the same time disengage the locking-lever from said sleeve to permit the fuse-body to be fully screwed into its sleeve and lock the fuse-ring 41 90 against rotation by pressure of the sleeve on the fuse-ring 40, for the purpose set forth.

In witness whereof I have hereunto set my hand in presence of two witnesses.

RASMUS HAGBARTH QUISLING.
